A. E. TOLIN.

TANK APPARATUS FOR PNEUMATIC CLEANERS.

APPLICATION FILED OCT. 7, 1914.

1,165,040.

Patented Dec. 21, 1915.

UNITED STATES PATENT OFFICE.

ALBERT E. TOLIN, OF ANDERSON, INDIANA, ASSIGNOR TO EXCELLO MANUFACTURING COMPANY, OF CHICAGO, ILLINOIS, A CORPORATION OF ILLINOIS.

TANK APPARATUS FOR PNEUMATIC CLEANERS.

1,165,040.

Specification of Letters Patent. Patented Dec. 21, 1915.

Original application filed December 4, 1913, Serial No. 804,704. Divided and this application filed October 7, 1914. Serial No. 865,457.

To all whom it may concern:

Be it known that I, ALBERT E. TOLIN, a citizen of the United States, residing at Anderson, in the county of Madison and State 5 of Indiana, have invented certain new and useful Improvements in Tank Apparatus for Pneumatic Cleaners, of which the following is a specification.

My invention relates to pneumatic cleaning apparatus of that type in which dust laden air is caused to pass through an air-cleaning liquid, and relates more particularly to the air cleaning tank or reservoir feature of such apparatus, and to various 10 combinations of cleaning apparatus elements therewith.

This application is a division of my co-pending application filed December 4, 1913, as Serial No. 804,704 on pneumatic cleaning 15 apparatus, patented the fifth day of January, 1915, as No. 1,123,426 to which reference is made.

The principal objects of the present invention are to provide a cleaning tank or receptacle for pneumatic cleaners which will automatically maintain therein a suitable 20 quantity of air cleaning liquid when properly connected with a source of liquid supply; to provide a tank apparatus which, in association with a suitable source of compression and a valve or valves for controlling the same, will permit the thorough 25 cleaning of the tank of liquid and accumulated dirt by means of such pressure; to provide, in combination with air-current generating and deflecting means, tank apparatus which will afford a proper cleaning 30 of dirt laden air and the flushing or cleaning of the tank by merely changing, by such deflecting means, the direction of the air current from said source; to provide tank apparatus which, in combination with other suitable elements of a cleaning device, may be kept in operative condition for cleaning 35 by means largely automatic, and, where not automatic, requiring but little effort on the part of the operator, such as merely turning a valve; to provide tank apparatus of the character described by which, in combination 40 with a suitable source of air current and deflecting means for same, cleaning may be

done in the rooms of the building wherein the apparatus is installed and the tank emptied and re-supplied with clean water without stopping or reversing the air current, 55 and the tank cleaning operation performed without materially interfering with the room-cleaning operation; to provide means in a tank of the character described adapted to prevent back flow, as from a sewer into 60 the tank; and to provide air cleaning tank apparatus adapted to have automatically maintained therein a constant quantity of air cleaning liquid.

General objects are to provide tank apparatus of the character described of simple construction, compact in form, and effective 65 of operation.

Still other objects will appear hereinafter.

In the accompanying drawings, which 70 form a part of this specification I have illustrated a preferred embodiment of the improvements to which reference has been made, Figure 1 being a side elevation of a cleaning device complete including my improved tank, a source of air current, means for operating the same, and an air-current valve device co-operating therewith. Fig. 2 is an enlarged vertical longitudinal section taken medially through the structure of Fig. 75 1, except that a modified arrangement of the inverted trap 19, 21 and 21' from that of Fig. 1 is shown, one part thereof being positioned within the tank. Fig. 3 is a vertical transverse sectional view through the valve 80 mechanism of Fig. 2, as on the line 3—3 thereof; Fig. 4 is a similar section on the line 5—5 of Fig. 2.

The substantially air and liquid tight tank, container or reservoir 10 is adapted 90 partially to be filled with a substantially constant quantity of air-cleaning liquid, such as water, the normal liquid line 12 of which is maintained at its proper elevation in part by means of an automatic valve 13 in operative communication with an intake liquid supply pipe 14 connected with a source of supply (not shown) and controlled preferably by a float, as 15, this automatic float valve being shown merely conventionally in 95 Fig. 2. It will be apparent that should the liquid 11 fall below the normal liquid line 100

12, the valve 13 will open, permitting additional liquid to enter the tank until the normal liquid line is again reached when the valve will automatically close, stopping the supply. Above the liquid body 11 in the tank is an air space 16.

A discharge pipe or conduit 19 is provided having its opening into the tank, as 19', preferably at or close to the bottom of the tank, which conduit may be entirely within the tank as illustrated in Fig. 2, but which may be positioned outside the same, as in Fig. 1. This pipe or conduit 19 extends upward to substantially the normal liquid line 12 where a bend is made in the direction of the pipe, whence it extends downward, as at 21', and may be connected to a waste reservoir or sewer. As shown in the drawings, I preferably provide a short, slightly declining or substantially horizontal portion 21 at the top of the inverted trap thus formed, and suitably in connection with this portion 21 I provide an automatic valve device 22, which may comprise a hinged plate as 22', the valve being adapted to open when water and dirt are discharged through the conduit 19 and to close should there be any back flow or pressure from the sewer, thus preventing sewer contents from entering the receptacle 10. Such automatic valve device, as 22, may, of course, be positioned elsewhere in the conduit than as illustrated, and may be of any other suitable check valve construction. This arrangement of the outlet provides also for the discharge of superfluous or excess water from within the tank 10, for, as is clear from Fig. 2, such excess water will flow out of the tank through the valve device 22 by gravitation. Means are thus provided for automatically maintaining in the tank the desired quantity of liquid for the effective operation of the machine.

Within the receptacle 10, and preferably secured to the upper wall thereof, as by threading the same into the boss 41, I provide an air-cleaning discharge nozzle 42 having its hollow interior in communication with the service pipe 39 through ports of the air-deflecting valve device shown. From a point at or preferably somewhat below the normal liquid line 12, this pipe or nozzle 42 is provided with relatively long and narrow longitudinal slots or air discharge apertures 42', preferably V-shaped, and preferably open at the bottom, whereby, among other notable advantages, during the discharge of water from the tank through the conduit 19 solid matter caught in the apertures 42' will be freed by the gradually enlarging walls thereof and carried away.

The operation and action of the tank device thus far specified may well be described in connection with a general description of its associated parts in the preferred and illustrated form of pneumatic cleaning de-

vice of which it is a part. In this preferred form the source of air current 23 consists of a well known type of rotary blower having co-operating vanes carried by spaced apart mandrels 24 and 25, and operated by the band wheel 26, the belt 27, the pulley 28 and the motor 29, all of these parts being secured upon or in connection with the tank device to form a unitary structure. In the various operations of providing suction or compression at the nozzle where cleaning of the rooms is being done, or in cleaning the tank, this blower may be continuously operated and in one direction. An air-deflecting valve is shown as connected to the tank at the top thereof, the valve casing 18 and the valve element 50 therein being provided with a number of co-operating ports which may well be described generally in describing the course of the air current through the machine.

The pipe 39 is the service pipe leading to various parts of the building where cleaning by suction or by blowing is to be done, and with which pipe is connected the usual cleaning nozzle at the end of a flexible tube, these usual parts not being shown by illustration. Assuming that suction is being had at such cleaning nozzle, the air current flows downward through the pipe 39, through the port 40 of the casing 18, the port 52 of the valve element 50, the port 43 of the casing 18, the nozzle 42 and the discharge openings 42' thereof, thence into the valve port 51 through the port 17 of the valve casing (see Fig. 4), whence the air current passes into the hollow portion 31' of the connection 32 and into the pipe 31, which pipe 31 is the intake pipe for the blower 23. After passing through the blower or source of air current 23, the current is preferably caused to pass into a settling chamber 33 through the opening 34, which settling chamber is adapted to permit dust-like particles or foreign matter in the air current to collect therein, should some dust or foreign matter escape into the blower through the liquid body 11. From the settling chamber 33 the current passes into the pipe or conduit 36, whence it passes through the casing port 38 and the valve port 53 (shown in dotted lines in Fig. 2), thence through the casing port 54 and into the pipe 55, whence it may be conveyed to any suitable point and be discharged into the open air.

When it is desired to have compression at the cleaning nozzle associated with the service pipe 39 the valve handle 65 is given substantially a one-eighth turn to the left while facing it, or toward the person viewing the same from the side illustrated in Fig. 1. The valve element 50 is thus moved so that the parts at the left-hand end thereof are in the dotted line position shown in Fig. 4, from which it will be observed that, as the

blower continues to be operated as before, the air current will continue to pass in the direction indicated by the arrow in the pipe 31, the port 56 (Fig. 4) now being the intake, the port 17 of the valve casing being closed by the part 50^a. The air now passes through the blower, settling chamber, pipe 36, and into the port 38 of the valve casing as before. The port 57 (not in communication with the port 53) is now in communication with the port 38, and as this port 57 is also in communication with the port 52, and as this port 52 or the enlargement 52' thereof is in communication with the pipe 39 (see Fig. 3), and as the port 57 has also come into communication with the port 43, it is apparent that the air current will flow simultaneously upward into the service pipe 39 and downward into the cleaning nozzle 42. However, as there is now no escape for the air from the cleaning tank 10 except through the conduit 19, and, as forcing the water out of the tank requires considerable pressure, the effect is that a blowing current is provided at the cleaning nozzle for cleaning purposes. Should it be desired to empty the tank and clean the same while compression is thus being had at the cleaning nozzle, it is only necessary to stop the flow of the current at the nozzle, as by means of a valve with which such nozzles are usually provided, thereby discharging downward into the pipe 42 all of the air current generated by the blower, which causes the tank contents to be forced, from the bottom portion thereof where the dirt has accumulated, past the valve 22 and into the sewer, a quantity of additional water flowing into the tank the while through the valve 13 and assisting in the flushing of the tank. As soon as the pressure is taken off the interior of the tank the tank again automatically fills with water to the desired height.

As it is not always desirable to flush the tank by merely closing the cleaning nozzle valve, the ports of the valve element 50 are so formed that by giving the valve handle 65 an additional one-eighth (or a total one-fourth) turn in the direction mentioned the action is as just described except that no air current passes into the service pipe 39. Fig. 2 shows the port 57 as of such width as to permit of two substantially one-eighth turns of the valve 50 before this port 57 passes out of registration with the ports 38 and 43, and Fig. 4 shows the port 51 of sufficient width to allow of intake at the port 56 when the valve is given a full one-fourth turn.

The various parts shown may be of the usual materials employed in devices of this general kind and the making thereof will be well understood by those skilled in the art. It will also be clear to persons skilled in the art that various modifications may be made

in the form and arrangement of parts shown without departing from the spirit of the invention disclosed. All such modifications and changes are contemplated by me as fall within the scope of the appended claims. 70

I claim:

1. In pneumatic cleaning apparatus, the combination of a tank adapted to be filled partially with an air-cleaning liquid, a service pipe and a source of air current in communication with the interior of said tank, means for alternately producing suction and compression in said tank from said source, and means including an automatic valve adapted to provide a passage for the discharge of liquid from said tank when pressure from said source is applied upon the liquid within the tank. 75

2. In pneumatic cleaning apparatus, the combination of a tank adapted normally to be filled partially and substantially to a predetermined normal liquid line therein with an air-cleaning liquid, means including a service pipe for conveying dust laden air to the interior of said tank, a source of air current in suction communication with the interior of said tank, means for automatically introducing liquid into said tank until the normal liquid line thereof is reached whenever during the operation of the device 95 the liquid in said tank falls below such normal liquid line, and means for automatically discharging a quantity of the liquid from said tank when said liquid rises above said normal liquid line, whereby a substantially 100 constant quantity of such liquid is maintained in said tank, said automatic discharge means including a check valve adapted to close against a back flow of liquid therethrough. 105

3. In pneumatic cleaning apparatus, the combination of a tank adapted to be filled partially and substantially to a normal liquid line therein with an air-cleaning liquid, means including a service pipe for conveying dust-laden air to the interior of said tank, a source of air current, means for placing said source of air current alternately in suction and compression communication with the interior of said tank, means adapted 110 automatically to discharge from said tank liquid rising above such normal liquid line, said means being also adapted to discharge liquid from said tank when the surface thereof is below said normal liquid line and 115 compression is applied upon the surface thereof in said tank, and means for automatically supplying liquid to said tank when the liquid therein falls below such normal liquid line. 120

4. In pneumatic cleaning apparatus, the combination of a tank adapted to be filled partially with air-cleaning liquid and to a normal liquid line therein, means for conveying dust laden air to the interior of said 125 130

5 tank, a source of air current, means for placing said source of air current alternately in suction and compression communication with the interior of said tank, means adapted to provide a discharge of liquid from said tank when pressure is applied upon the liquid in the tank, and means for automatically introducing liquid into the tank until the normal liquid line thereof is again 10 reached after such pressure is removed.

15 5. In pneumatic cleaning apparatus, the combination of a tank adapted normally to contain an operative quantity of air cleaning liquid, said tank having an air space in the upper portion thereof, a service pipe adapted to carry dust laden air to the interior of said tank, means for providing suction in such upper portion, and means for automatically introducing liquid into said 20 tank until the normal liquid line thereof is reached, the operation of said last mentioned means being independent of said suction providing means, means for applying compression in the upper portion of said tank, and 25 means dependent on such compression for discharging the contents of said tank.

30 6. In pneumatic cleaning apparatus, the combination of a tank adapted to contain an operative quantity of air cleaning liquid, a service pipe, an air discharge nozzle in communication with said service pipe and having a discharge portion thereof below the liquid line of such operative quantity of liquid in said tank, a source of suction in communication with the interior of said tank adapted to cause air to flow through said service pipe and discharge nozzle and through liquid in said tank, and means including an automatic intake valve and an 35 automatic outlet valve for automatically maintaining an operative quantity of liquid in said tank during the operation of the machine, said outlet valve being adapted to close against the back flow of liquid there- 40 through.

45 7. In pneumatic cleaning apparatus, the combination of a tank adapted to contain an operative quantity of air cleaning liquid, an air discharge nozzle having a discharge opening therein below the normal liquid line of such operative quantity of liquid in said tank, a source of suction in communication with the interior of said tank adapted to cause air to flow through said discharge 50 nozzle and through liquid in said tank, and means for automatically maintaining the liquid in said tank above said discharge opening in said nozzle during the operation of the machine, means for providing compression in said tank above the liquid body thereof and means dependent on such compression adapted to provide a discharge from the tank of substantially the contents thereof.

60 8. In pneumatic cleaning apparatus, the

combination of a tank adapted to contain an operative quantity of air-cleaning liquid, a service pipe in communication with the interior of said tank and opening thereinto below the normal liquid line thereof, a 70 source of air current, valve means for controlling the air current from said source whereby suction and compression may alternately be had in said tank, a liquid discharge pipe connected to said tank and 75 opening thereinto close to the bottom thereof, said discharge pipe thence extending upward to the normal liquid line of said tank and thence turning and extending downward, forming an inverted trap. 80

9. In pneumatic cleaning apparatus, the combination of a tank adapted to contain an operative and substantially constant quantity of air-cleaning liquid, a service pipe and a source of suction in communication with the interior of said tank, a discharge pipe connected to said tank and opening thereinto close to the bottom thereof, said discharge pipe thence extending upward to the normal liquid line of said tank and 90 thence turning and extending downward, forming an inverted trap, a check valve in said discharge pipe adapted to provide escape of liquid from said tank, and means for applying compression in the space above 95 the liquid body in said tank.

10. In pneumatic cleaning apparatus, the combination of a substantially air tight and water tight tank adapted to be filled partially with an operative quantity of air-cleaning liquid, means for supplying liquid to said tank, a float valve in said tank and associated with said means, said valve being adapted to provide an opening for liquid to flow into said tank until a predetermined 100 normal liquid line thereof is reached and then to close such opening to stop the flow of liquid thereinto, a service pipe in communication with the interior of said tank and below the normal liquid line therein, means for alternately producing suction and compression in the space above the liquid body in said tank, and means for providing escape for liquid from said tank when pressure greater than atmospheric is applied 105 upon the liquid in said tank. 110

11. In pneumatic cleaning apparatus, the combination of a tank adapted to contain an air-cleaning liquid, a service pipe, and a source of air current in suction communication with the interior of said tank, and a discharge pipe having an opening within said tank operatively close to the bottom portion thereof and lower than the normal liquid line in said tank whereby substantially all of the liquid in said tank may be discharged through said pipe, said pipe having a direction upward to a point substantially on a plane with the normal liquid line in said tank, and thence extending in 115 120 125 130

such direction that as the liquid in said tank rises above the normal liquid line thereof it will flow by gravitation through said discharge pipe, thereby automatically maintaining said liquid at substantially its normal liquid line in said tank, said discharge pipe having an automatic valve adapted to

provide an opening for liquid in said tank to flow therefrom and to close such opening to prevent a back flow into said tank.
